SHOE-CLEANING MACHINE WITH RECIPROCATING CLEANING ELEMENTS

Percell L. Drake, Detroit, Mich.

Application February 20, 1946, Serial No. 648,872

3 Claims. (Cl. 15—4)

1

This invention relates to improvements in shoe cleaners, and more particularly to a shoe cleaner which will be positioned at the entry of a house or office, whereby a person with snow or mud on his shoes may clean them before entering the house or office.

An object of the invention is to provide an improved shoe cleaning device which will include an outer casing or pan for collecting the mud or snow as it is removed from the shoes, and a pivoted shoe scraper and wiper for cleaning the soles of the shoes, together with a brush for brushing the uppers of the shoes.

Another object of the invention is to provide an improved manually operated shoe cleaner, which will be highly efficient in operation and relatively inexpensive to manufacture and produce.

Other objects will appear as the description proceeds.

In the accompanying drawings which form a part of this application,

Figure 1 is a side elevation of the improved shoe cleaner showing a shoe in position thereon;

Figure 2 is a plan view of the improved shoe cleaner;

Figure 3 is a longitudinal sectional view taken on the line 3—3 of Figure 2;

Figure 4 is a side elevation of the shoe cleaner device in inoperative position;

Figure 5 is a partial sectional view taken on the line 5—5 of Figure 4, and

Figure 6 is an enlarged sectional view taken on the line 6—6 of Figure 4.

Like characters of reference are used throughout the following specification and the accompanying drawings to designate corresponding parts.

In carrying out the invention, there is provided an outer receptacle 1 which is substantially rectangular in shape and is provided at its open upper edge with the laterally extending flange 2'.

Positioned within the receptacle 1 is the supporting frame formed with the oppositely disposed side frame members 2 and 3, the same having laterally extending flanges 4 and 5 at the upper and lower edges, respectively. An end member 6 is connected between the adjacent ends of the side frame members 2 and 3.

An inverted U-shaped shoe support 7 is fixed to the opposite side frame members 2 and 3 by the rivets or fasteners 8, at a point adjacent one end of said frame members, and is adapted

2

to support the arch portion of a shoe, as shown in Figure 1 of the drawings.

A slideable cleaner frame comprises the two side members 9 and 10, and a connecting end member 11. Cross shafts 12 and 13 are secured between the side members 9 and 10 adjacent their opposite ends, and support the rollers 14 and 15, which are adapted to roll on the upper flanges 4 on the side frame members 2 and 3, thus supporting the slideable cleaner frame on and above the supporting frame positioned in the receptacle 1.

The inverted U-shaped metal shoe sole scraper 16 is mounted at an angle between the side members 9 and 10 of the cleaner frame, and is used to scrape the mud or snow from a shoe sole.

The inverted U-shaped shoe sole wiper 17 is mounted at an angle between the side members 9 and 10 of the cleaner frame at a point adjacent the sole scraper 16, and comprises the rubber strips 18 and 19 mounted between the metal backing strips 20 and 21, and detachably supported on the wiper 17 by means of the bolt 22 and nut 23.

A brush member 24 is mounted between the side members 9 and 10 of the cleaner frame at a point near the scraper 16 but on the opposite side from the wiper 17. The brush member 24 is of inverted U-shape and includes the depending brush 25 supported between the body member 24 and a backing plate 26, and held in position by means of the screws 27, in such a manner that the shoe upper may be brushed when the brush member 24 secured between the side members 9 and 10 of the cleaner frame is reciprocated back and forth with said cleaner frame.

The bearing rod 28 is mounted between the side frame members 2 and 3 and extends laterally thereof at one end to pivotally support the operating link 29. A second operating link 30 is pivotally supported on the end of the cross shaft 13, and extends upwardly to meet the upper end of the link 29, and to be connected thereto and to the lower end of the shank 31 of the operating handle 32. A vertically extending slot 33 is formed in the shank 31, and slidably receives the pin 34 to which are connected the depending connecting links 35 and 36, which are secured at their lower ends by means of the rivets or fasteners 37 and 38 to the operating links 29 and 30.

From the foregoing description, the mode of operation of the improved shoe scraper will be readily understood. When it is desired to clean one shoe at a time is cleaned by step-

ping on the shoe support 7, and then grasping the operating handle 32 and vertically reciprocating the same, the mud or snow being scraped from the shoe sole to drop in the receptacle 1, after which the wiper 11 will wipe the shoe sole dry, and the toe of the shoe will be brushed off as the brush 25 reciprocates over it. A tensioning spring 39 will be connected between the operating links 29 and 30 to urge the same to their upper position when the cleaner is not in actual operation.

While the preferred embodiment of the invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. In a shoe cleaner, a pair of parallel co-extensive rails, a frame mounted to reciprocate on said rails, a support on said rails adjacent one end of the rails for a shoe, cleaning members on said frame, an inflexible link pivoted at one end thereof to one of the rails at said one end of the rails, a second inflexible link pivoted at one end to the end of said frame remote from said one end of the rails, a handle, the other ends of said links being concentrically pivoted to said handle so that reciprocation of the handle reciprocates the frame on the rails and causes said cleaning members to frictionally engage the shoe on said support.

2. In a shoe cleaner, a pair of parallel co-extensive rails, a frame mounted to reciprocate on said rails, a support on said rails adjacent one end of the rails for a shoe, cleaning members on said frame, an inflexible link pivoted at one end thereof to one of the rails at said one end of the rails, a second inflexible link pivoted at one end to the end of said frame remote from said one

end of the rails, a handle, the other ends of said links being concentrically pivoted to said handle so that reciprocation of the handle reciprocates the frame on the rails and causes said cleaning members to frictionally engage the shoe on said support, and means to preserve said handle in vertical position comprising a pair of links having one end of each link concentrically vertically slidably and pivotally mounted on said handle, the pivotal mounting of said pair of links being spaced vertically from said concentric pivotal connection of said inflexible links to said handle, and the other ends of said pair of links being pivoted on intermediate portions of said inflexible links.

3. A shoe cleaner according to claim 2 and wherein said pivotal mounting of said pair of links comprises a vertical slot in said handle, a pin slidably mounted in said slot, and said one end of each link of said pair of links being pivotally secured to said pin.

PERCELL L. DRAKE.
